RUNNING GEAR CORRECTING APPARATUS

Sidney W. Martin, Chicago, Ill.

Application December 31, 1935, Serial No. 56,972

5 Claims. (Cl. 153—38)

This invention relates to checking and aligning devices for the running gear of vehicles, being particularly applicable to wheel, axle and steering gear portions of automobiles. An important object of the invention is the provision of means whereby the entire steering geometry and alignment of the supporting portions of the steerable wheels of a vehicle may be checked, and any inaccuracies and their extent determined, and whereby faults or inaccuracies so disclosed may be corrected.

Another important object is the provision of an improved and simplified checking device for determining the caster, camber and kingpin inclination of the steerable wheels of a motor car.

Still another object is the provision of improved means for checking the toe-in of such wheels.

A further object is the provision of means for simultaneously checking the steering radius of both front wheels, and determining any inaccuracies in the relationship thereof and their extent.

Still another object is the provision of improved checking means for determining axle inclination.

A still further object is the provision of an improved and simplified bending device for correcting axle deformation, whereby the axle or equivalent wheel-supporting portions of a motor car may be bent or twisted in any desired direction, while cold, without removing the same from the car, and without even the necessity of removing the wheels, thereby enabling correction of disaligned steering elements as well as the straightening of axles and the like.

Other objects and advantages will be apparent from the following description, wherein reference is made to the accompanying drawings illustrating a preferred embodiment of my invention, and wherein similar reference numerals designate similar parts throughout the several views.

In the drawings:

Figure 1 is an elevational view of a front wheel of a motor car, showing one of my improved checking instruments attached thereto;

Figure 2 is an enlarged plan view of the checking devices and its supporting means, sectionally showing a wheel spoke to which the device is clamped;

Figures 3, 4 and 5 are sectional views taken substantially on the lines 3—3, 4—4 and 5—5 respectively of Figure 2, and looking in the direction of the arrows;

Figure 6 is a plan view of the bottom of the instrument;

Figure 7 is a plan view of another improved checking device for determining inaccuracies of turning radius, also sectionally and fragmentarily showing a wheel and adjacent supporting portions of a motor car in conjunction with which the device is adapted to be used;

Figure 8 is a side view of the instrument;

Figure 9 is an end view thereof fragmentarily showing a wheel in elevation;

Figures 10 and 11 are plan views of the indicator plates or scales used upon such checking devices;

Figure 12 is a plan view of a front axle and wheel assembly showing two complementary checking devices of this type, in use, one upon each front wheel, indicating the manner in which they are used cooperatively upon both front wheels of an automobile simultaneously;

Figure 13 is a view similar to Figure 12 of a somewhat modified form of the invention;

Figure 13a is an enlarged plan view of the adjustable scale portions of this embodiment;

Figure 14 is a fragmentary sectional view of the front wheel of a motor vehicle, showing in side elevation one of the instruments of Figure 13;

Figure 15 is an elevational view of a front wheel and axle assembly of a motor car, sectionally showing the front springs, indicating the use and showing the construction of one of my improved axle levels, forming another element of my checking apparatus;

Figure 16 is an enlarged fragmentary front elevational view of the axle level and its supporting means;

Figure 17 is a section taken substantially on the line 17—17 of Figure 16 and looking in the direction of the arrows;

Figure 18 is a view similar to Figure 15 of the front axle and wheels of a motor car, showing one of my improved toe-in gages appurtenant and as used in conjunction with the same for gaging toe-in;

Figure 19 is a side view of the front portions of a motor car, also indicating the use of the toe-in gage in checking the relation of the front wheels;

Figure 20 is a front view of the indicator portion of the device;

Figures 21 and 22 are vertical sections taken substantially on the lines 21—21 and 22—22 respectively, of Figure 18, and looking in the direction of the arrows;

tion of the arrows, the wheels appurtenant in the latter view being omitted;

Figure 23 is an elevational view of one of my improved axle-bending devices, with the shackle or yoke portions removed;

5 Figures 24, 25 and 26 are perspective views showing, in conjunction with a motor car front axle, one of my improved bending devices in use, and in positions enabling bending the same in various directions; and

10 Figures 27 and 28 are similar views showing the device in use for twisting the axle in different ways.

15 Referring now to the drawings, and particularly to Figures 1 to 6 inclusive, reference character 25 designates a housing, which may be generally T-shaped, as best shown in Figure 2, which carries two spirit inclinometers 27-29 arranged at right angles to each other and visible from the 20 top face of the instrument. The inclinometer 29 carried by the stem portion of the T is provided along opposite sides with caster and camber calibrations, as 30, 31 respectively, preferably reading in degrees, while the transverse inclinometer 27 carried by the head portion of the T-shaped body is calibrated, preferably also in degrees, to designate kingpin inclination, as at 33.

25 At a suitable point, here shown as the top mid-portion of the head of the T-shaped body, the 30 device is connected as by means of a ball and socket joint (the ball being designated 35 and the socket portion 36) to a clamping device 38, by means of which the instrument may be secured to a suitable portion of a vehicle wheel. It is here shown clamped to the spoke 40 of an artillery wheel, and the illustrated clamping device comprises a fixed jaw 41, and a movable jaw as 42, which latter may be forced toward or retracted from the fixed jaw by means of a thumb-screw 43.

35 Also carried by the body portion of the instrument and visible only from its rear face, are a pair of spirit levels, as 45-46, arranged perpendicularly to each other and one carried by the head and the other by the stem portion of the casing.

40 As best shown in Figures 3, 4 and 5, the casing of the instrument may be hollow, and the inclinometer and level tubes may be positioned in an initially plastic material such as plaster of Paris which sets or rigidifies upon standing, to hold them in place. The supporting mass in which the tubes are embedded is designated 41.

45 Each level is so related to the opposing inclinometer which lies opposite it in the same branch of the casing that when the instrument is inverted and the level bubble is centered, the opposite inclinometer would read at zero if the instrument were rotated 180 degrees about a horizontal axis.

50 The camber calibrations 31 appurtenant the inclinometer 29 are so disposed that when the instrument is attached to a front wheel at a point spaced from its axis, as shown in Figure 1 for example, with the stem of the casing projecting substantially perpendicularly from the plane of the wheel, and the device is first leveled in inverted position by means of the levels 45-46, upon turning the wheel through 180 degrees, which may be done by merely rolling the car until the wheel has turned a half revolution, the bubble in the inclinometer will designate on the camber calibrations the camber angle of the wheel.

55 The caster calibrations 30 are so disposed that 75 when the instrument is similarly clamped to the

wheel, face up, and with the inclinometer 29 projecting substantially perpendicularly from the plane of the wheel, and with the wheel turned to a definite steering angle (a given number of degrees from the straight-ahead position) after which the inclinometer bubble is centered by tilting the instrument until the bubble rests at zero on scale 31, the wheel may be turned about its steering axis to an equal angle in the opposite direction, and the bubble will designate degrees of 10 caster upon scale 30.

15 The scale 33 is so calibrated with relation to the inclinometer 27 that by a similar operation, upon swinging the wheels from an initial steering angle and positioning the bubble at zero by leveling the instrument, and then turning the wheel to an equal but opposite steering angle, the bubble will move to a position designating the degree of kingpin inclination on the scale.

20 It will be seen that this instrument may be clamped to and leveled at any portion of the wheel spaced from its axis, and by simple movements of the wheel, which may be performed without jacking up the car by merely rolling the car to turn the wheel through a desired angle, 25 and by swinging the wheels about the steering knuckles, the kingpin inclination, caster and angles may be very quickly and accurately determined.

25 Before beginning any such gauging operations 30 as those just described, it is desirable either to see that the axle or other member to which the wheels being checked are attached is level, or determine the degree of its inclination if out of level. My preferred construction for determining 35 axle inclination, as shown in Figures 15, 16 and 17, comprises a bar inclinometer 50 calibrated in degrees, as at 51, and carried by hooks 53-54 of equal length, projecting upwardly from opposite ends of the bar, and one of which, as 54, 40 may be slidable along the bar, over which it is accurately fitted, as best shown in Figure 12. Friction means for holding it against undesired movement is provided in the form of a spring-pressed ball 55. The supporting hooks 53-54 45 may also be provided with downwardly projecting lugs, as 56 of reduced size and accurate length, to facilitate forcing the hooks downward into proper metallic contact with the top of the axle through dirt or other foreign matter, as best 50 shown in Figures 10 and 12.

55 If by means of inclinometer 50 the axle is determined to be out of level, allowance may be made for such condition by simply adding to or subtracting from the camber and kingpin inclination readings the number of degrees which the axle is out of level. The taking of these readings all in degrees by both the checking instrument first described and the axle inclinometer makes possible such corrective allowance.

60 In order to determine the degree of toe-in of the front or steerable wheels I preferably employ the device shown in Figures 18 to 22 inclusive. A pair of upstanding abutment supports, as 60-61, are carried by a tubular cross frame 62. One abutment element, as 60, is rigidly although adjustably affixed to the tube or rod 62, as by means of a removable pin 63, which may be inserted in any of several holes as 64 in the tube, and projects through the base of the support 60 to lock 70 it in desired position. An outwardly projecting contact element 65 is carried by the top of the support 60, and at the top of the opposite support 61 an adjustable contact element is formed by the thumbscrew 66. Thumbscrew 66 is car- 75

ried by the upwardly projecting extremity of an indicating needle 67, which is pivoted on a transverse axis over the frame 61, and at its lower extremity adapted to sweep a scale 68.

5 In operation, it will be seen that coarse or initial adjustment of the distance separating the abutments may be made by means of the pin 63 and corresponding apertures 64. Thereafter the instrument is positioned with the abutment members 65, 66 bearing against the sides of the tires of the two front wheels of the car, preferably as far forward as is practicable, in the manner shown in Figure 18 and in full lines in Figure 19. The thumbscrew 66 is then turned 10 until the needle 67 is centered at zero, after which the entire device is moved to a position in which its contacts similarly bear against the tires in a similar position at the rear part of the circumference of the wheels, as indicated in 15 dotted lines in Figure 19. When the abutments 65-66 are thus similarly forced against the sides of the tires at the rear, the needle will be moved to a different position in accordance with whatever difference in the distance separating 20 the front and rear portions of the tire may be present, and the relative movement of the needle which has taken place may be observed to determine the extent of toe-in. This determination may also be made without taking the weight 25 of the car off the wheels, although preferably when the instrument is moved from the front to the rear position, the car is rolled sufficiently to so turn the wheels that in making the rear reading the abutments may engage the same 30 points on the tires as they did in making the front reading, thereby preventing wheel or tire irregularities from affecting the reading. The multiplication of the relative movement of the contact by the length of the needle 67 will be 35 seen to make possible very accurate determination of the degree of toe-in.

In order to check the accuracy or determine the extent of any incorrectness of the angular movements of the wheels during steering, I preferably employ the construction shown in Figures 7 to 12 inclusive, comprising a frame or base 10 having short legs, as 71, adapted to support it beside the front wheels of the car under test upon the floor or other surface upon which it is standing. Pivoted upon the nose of the triangular base 10, as upon a pin 75, is a pointer 72 arranged to sweep a scale formed in cooperating sections carried by separate plates 73-74. The scale plates are mounted upon the broader 40 rear end of the base, and one, as 74, is slidable relatively to the other toward and from the pivot bolt 75, being shown adjustably secured to the base 10 by means of screws 80 passing through slots 81 in the plate.

45 Also swingably movable with the needle 72 and pivotal about the bolt 75 is a transverse bar 76 to which is pivoted on a horizontal axis a swinging frame 77, which carries at its end a transverse wheel-engaging rod 78 adapted to extend across and contact the outer side wall of a tire at two points, as best shown in Figure 9, when the device is positioned beside the wheel and the rod leaned thereagainst. A tension spring, as 79, may also be provided to assist in urging the 50 rod against the wheel, stretched between the nose of the base 11 and the top of the swinging frame 77.

55 Preferably a pair of these instruments are used simultaneously, one against each front wheel, in the manner best shown in Figure 12, in check-

ing the turning geometry of the car, and the opposing instruments of the pair are similarly constructed, but oppositely calibrated. The reversed arrangement and calibration of the indicator plates used on right and left side instruments is clearly brought out in Figures 10 and 11 respectively. One of the scale or dial plates on each instrument, as 73-73a, may have its scale portion (82-82a) calibrated in degrees of turning radius, while the other dial plate of each, 10 as 74-74a, may be so calibrated, as at 83-83a, that when in use during a checking operation, and the equivalent needle on the opposite instrument of the pair designates any given number of degrees of turning radius of its front wheel 15 (on the scale 82-82a) the needle 72 will indicate on the scale 74 a line having the same numerical value if the wheels are correctly adjusted.

In order to compensate for the differences of 20 tread and wheel base of various cars, the plates 74-74a may be adjusted in position toward and from the pivot bolt 75 by means of the screw and slot securing means above described. To determine the proper positioning of these plates the side of each abutting the plate 73-73a may 25 be provided with an edge scale, as 85-85a, calibrated in wheelbase values, while the adjacent edge of the plate 73-73a is provided with a cooperating scale 84-84a calibrated in tread or track values; these indicia being so arranged 30 that when the line designating the tread of the car under test is aligned with that indicating the wheel base of the car, the scale 74 is in a proper position for determining the propriety of the relationship between the wheels in cooperation with the scale of the opposite instrument.

In the somewhat modified construction shown in Figures 13, 13a and 14, the body of the chart or scale portion of the indicator is formed in two sectoral plate sections 90-91 pivoted together as by the pivot bolt 75a to permit their angular adjustment relatively to each other. The plates 90-91 are adapted to rest flat upon the floor and are provided with overlapping scale portions 84a-85a, calibrated in tread and wheel 40 base respectively, for adjusting the instrument to cars of different dimensions in a manner analogous to the scale adjustment provided in the embodiment last described by the movability of plate 74. Along the edges of the plates 90-91 45 are ruled a plurality of parallel lines, calibrated on one plate in degrees of turning radius and on the other calibrated to indicate the same numerical value when with the scale plates properly adjusted and the wheels properly aligned, 50 the opposite wheel is turned to any given angle. The sections 85 calibrated in degrees and the sections 82 calibrated arbitrarily to agree numerically when the relationship between the wheels is correct are disposed oppositely on the 55 units for the two wheels, as shown in Figure 13.

In this embodiment the pointer 72a is directly attached to the wheel, as by means of the clamp 86 and articulated arms 87-88, the former attached to the clamp 86 by a ball and socket joint 65 89, and the latter pivotally attached to the pointer, which is thereby held spacedly above the scale portions carried by the plates, for free swinging thereover upon turning the wheels about their steering axes. It will be seen that in order to initially position the apparatus it is only necessary to set the wheels straight ahead and so arrange the plate assemblies 90-91 on the floor beside the opposite wheels to be tested, and so connect the pointers thereto that the latter indicate zero with 70 75

the wheels in that position. The plates are of course preliminarily adjusted for the track and wheelbase of the car. Thereafter, upon swinging the wheels in either direction, the numerical values indicated by opposite pointers should be equal, and if they are not, the extent of the inaccuracy is of course indicated by the extent to which they vary.

For bending the axle to correct inaccuracies disclosed by the described checking devices, as well as to correct distortion of the axle itself, I preferably employ the device shown in Figures 23 to 28 inclusive, comprising a heavy cast or forged frame 100 having a rigid arm 101 angularly projecting therefrom and yoked at its end to support a nut 102, which is trunnioned and rockable in the opposite arms of the yoke on its supporting stub shafts 103.

Pivottally attached to the farther end of the frame 100, as by means of the pin 104, is a bending arm 105, also bifurcated at its outer end and similarly pivottally supporting, as by means of the stub shafts 106, a traveler nut 107. The screw shaft 108, formed in two oppositely threaded halves, is threaded at its opposite ends into the nuts 102-107, and may be turned in any suitable fashion, as by means of the ratchet wrench 109, to swing the arm 105 toward and from the arm 101. The other end of the arm 105 projects from the opposite side of the fulcrum pin 104 and is provided with a nose portion 105a adapted to exert a powerful cam-like action against an axle or other adjacent part when forced thereagainst by means of the jack screw 108.

A plurality of transverse holes, as 111, 112, 113 and 114, extend through the frame 100 at various points therealong, and a similar aperture 110 extends through the arm 105 at a point spaced from its pivot pin 104 and clear of the frame 100. By means of the apertures 110-114 inclusive, and the removable coupling pins 115-115a, heavy looped shackling members as 116-117 are adapted to be secured to the frame 100 and the arm 105, as best shown in Figures 24 to 28 inclusive. These shackles may be passed over various portions of an axle or other work to be bent, in the manner shown, to grapple the straightening device thereto, and by the exertion of pulling force upon the shackles by means of the jack screw, bending stress may be exerted upon the axle.

In Figure 24 a typical utilization of the device is shown in which force is applied to the end of the axle to bend it down at the approximate point marked 118. This will be seen to effect an increase of the camber angle. When used in this fashion a block as 119 is interposed between the axle and a midsection of the body of the straightening device, while the bight portions of the shackles 116-117 are pulled downward against the top of the axle by so turning the jack shaft 108 as to force the arm 105 toward the arm 101.

A reverse bending operation is indicated in Figure 25, in which the shackle 117 will be seen to have been shifted to a point near the middle of the body of the device while the block 120 has been arranged between its fixed end and the upturned end of the axle in such manner that thrust transmitted therethrough may bend the axle upward. The arm 105 has been drawn in to an initial position in which it lies close to the arm 101, and it will be seen that when the device is applied to the axle in the manner shown and the arms forced apart by properly turning the

jack shaft, the nose 105a and thrust block 120 may be forced upward relatively to the midsection which is restrained by the shackle 117, to bend the end of the axle upward (also substantially about the point designated by the arrow 118), thereby to decrease the camber of a wheel carried by this end of the axle.

The arrangement of the device to perform a transverse bending operation upon an axle is shown in Figure 26. In this view the shackles 10 116-117 are arranged to exert a downward pull relatively to the centrally positioned interposed thrust blocks 121 when the arm 105 is moved toward the arm 101, in a manner which will be seen to be somewhat analogous to the bending 15 operation shown in Figure 24.

In order that twisting operations may be performed upon the axle, to enable changing the caster angle, I preferably provide a twisting bar, as 122, having a hooked end which is so formed 20 that it may be firmly engaged with the flanges of axles of conventional I-beam cross-section, in the manner clearly shown in Figures 27 and 28, while either end of the bending device may be arranged to exert pressure on the laterally projecting arm of the hooked member 22 in a desired direction, the body of the straightener being clamped to the axle in any of various ways, depending upon the direction and twisting effect desired. In Figure 27 the rigid end of the 30 straightener is shown secured to the upturned end of a conventional dropped axle, as by means of the shackle 117, while the movable nose portion 105a is so arranged against the laterally extending arm of the bar 122 that when the arms 35 101-105 are forced apart, a strong twisting effect may be exerted upon the axle, the twisting bar being secured to a mid-portion of the axle.

In Figure 28 the bending tool is shown in reversed position and farther in on the axle, while 40 the bar 122 is connected to the extremity of the axle. Here again tensile strain is exerted upon the centrally positioned shackle 117 and a reverse thrust upon the end of the twisting bar 122, which is thereby turned about its hooked 45 extremity to twist the end of the axle.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

What I claim is:

1. A bending device comprising a longitudinal 55 frame, a rigid arm extending laterally from one side of the frame, another arm pivottally attached to the frame at a point spaced from said rigid arm and having a portion projecting in the same direction as the rigid arm, said swingable arm 60 also having a shorter bending portion extending from the opposite side of the frame, means for securing an object to be bent to said frame between said arms, and jack means for moving said swingable arm with relation to the frame 65 and rigid arm, said arms and frame lying in substantially the same plane.

2. A bending device comprising a frame having pivot portions longitudinally spaced therealong, a rigid arm extending laterally from the 70 frame, a swingable bending arm laterally extensible from the frame near the other end and rockable with relation thereto about one of said pivot portions, said arms and frame lying substantially in the same plane, a jack articu- 75

lated to said arms, means for operating the jack 5 to swing the bending arm with relation to the frame, and grappling and bending portions securable to the frame at said spaced pivot portions and engageable with work desired to be bent, said bending arm being rockable with relation to the frame about either of a plurality of axes.

3. A bending device comprising a frame having 10 pivot portions longitudinally spaced therealong, a rigid arm extending laterally from the frame near one end, a swingable bending arm laterally extensible from the frame, near the other end and rockable with relation thereto about one of 15 said pivot portions, said arms and frame lying substantially in the same plane, a jack articulated to said arms, means for operating the jack to swing the bending arm with relation to the frame, and grappling and bending portions securable to the frame at said spaced pivot portions 20 and engageable with work desired to be bent, an additional pivot portion carried by said bending arm at a point spaced from its fulcrum and adapted to accommodate a grappling or bending 25 element which acts in tension when the arm is rocked.

4. A bending device comprising a rigid longitudinal frame, a pair of arms carried thereby and spaced from each other and projecting from the frame generally in the same direction, one of 5 said arms being rigid and the other swingable with respect to the frame, a cam-like bending portion carried by said swingable arm and pressure-exerting means for moving said arm with respect to the rigid arm, said arms and frame lying in substantially the same place.

5. A bending device comprising a rigid frame 10 having pivot portions longitudinally spaced therealong, a rigid arm extending laterally from the frame near one end thereof, a swingable bending arm laterally extensible from the frame 15 near the other end and rockable with relation thereto about one of said pivot portions, said arms and frame lying substantially in the same plane, a jack articulated to said arms, means for operating the jack to swing the bending arm 20 with relation to the frame, and grappling and bending portions securable to the frame at said spaced pivot portions intermediate the arms and engageable with work desired to be bent.
